US00D912191S

(12) **United States Design Patent** (10) **Patent No.:** **US D912,191 S**
(45) **Date of Patent:** **** Mar. 2, 2021**

(54) **HANDGUN MAGAZINE**

(71) Applicant: **Sig Sauer, Inc.**, Newington, NH (US)

(72) Inventors: **Adrian Thomele**, Stratham, NH (US);
Matthew A. Taylor, Barrington, NH (US)

(73) Assignee: **Sig Sauer, Inc.**, Newington, NH (US)

(**) Term: **15 Years**

(21) Appl. No.: **29/710,419**

(22) Filed: **Oct. 23, 2019**

Related U.S. Application Data

(63) Continuation of application No. 29/702,503, filed on Aug. 20, 2019, which is a continuation of application No. 29/632,273, filed on Jan. 5, 2018, now Pat. No. Des. 858,680.

(57) **CLAIM**

The ornamental design for a handgun magazine, as shown and described.

DESCRIPTION

FIG. 1 is a perspective view showing the right, front and top sides of a handgun magazine with our new design;

FIG. 2 is a perspective view showing the left, front, and top sides thereof;

FIG. 3 is a perspective view showing the right and rear sides thereof;

FIG. 4 is a perspective view showing the left and rear sides thereof;

FIG. 5 is an elevational view showing the right side thereof;

FIG. 6 is an elevational view showing the left side thereof;

FIG. 7 is a front elevational view thereof;

FIG. 8 is a rear elevational view thereof;

FIG. 9 is a top plan view thereof; and,

FIG. 10 is a bottom plan view thereof.

Broken lines in the drawings are for the purpose of illustrating environmental structure and form no part of the claimed design.

1 Claim, 10 Drawing Sheets
